UNITED STATES PATENT OFFICE

EGERTON RYERSON CASE, OF TORONTO, ONTARIO, CANADA

METHOD OF HEATING LIQUIDS

Original application filed March 7, 1927, Serial No. 173,443, and in Canada February 8, 1929. Divided and this application filed July 26, 1930. Serial No. 471,032.

My invention relates to improvements in method of heating liquids, and the object of the present invention (which is an application divided from the parent application, Serial No. 173,443, filed March 7th, 1927, for electric liquid heaters) is to maintain a highly-heated relatively-confined volume-constant body of fluid through which to pass a stream of confined liquid of a lower temperature in order to hasten rise in temperature thereof, and in the following specification and the drawings forming part thereof, I shall describe and illustrate two species within my invention, and what I claim as new will be set forth in the claims forming part of this specification.

Fig. 1 is a vertical central section through the preferred form of heater. Figs. 2 and 3 are horizontal cross sections respectively on the lines 2—2, and 3—3, Fig. 1, and Fig. 4 is a vertical central section through an alternative form of the heater.

In the drawings, like characters of reference refer to the same parts.

The preferred form of construction to put my method into practice, is illustrated in Fig. 1. The base or support 2 is preferably made in sections so that in case of breakage, any section may be readily replaced. The base is of course made of porcelain or any suitable insulating material. Each section is provided with a flange 3 which fits within a socket formed by an embracing flange 4 of the opposing section. Said sections are tubular in form, and the same are held together by a tubular, preferably metal, member 5 which passes centrally through said base. This tubular member 5 projects beyond both ends of the said base, and attached to the lower end thereof is an exteriorly positioned ring 6 which is partly located in a socket formed in the lowermost section of the base 2 as shown clearly in Fig. 1. A flanged member 7 is made of the same material composing the base 2 and is mounted on the tubular member 5 since it has a central passage-way therethrough, and it rests in contact with the topmost section of the base 2. This flanged member 7 is provided with a flange 8 which embraces the flange 3 of the topmost section of

said base 2. The flange 8 is used so that when the base 2 is removed any section thereof may be positioned in contact with the flanged member 7. Removably carried by the upper end of the tubular member 5 which projects above the flanged member 7, is a nut 9. The function of the nut 9 in co-operation with the member 5 and ring 6 is to hold the sections of the base 2 in co-operative relationship.

The sections of the base 2 are each provided with a plurality of spaced bars or ribs 10 extending longitudinally thereof, so that the resistor or heating element 11 may be "laced" longitudinally on said base. The upper ends of the ribs 10 forming part of the topmost section of the base 2 are spaced apart from the flanged member 7 so that the resistor 11 may be located between the said ends and the said flanged member. The lower ends of the ribs 10 of the lowermost section of the base 2 do not extend to the lower end of the flange 4 of said lowermost section, and therefore portions of the resistor or heating element 11 passing underneath the lower ends of the ribs of said lowermost section will rest in contact with said flange.

In order to tie the heating element or resistor 11 to the base 2 intermediate its end sections, after the resistor has been laced on the base, any of the intermediate sections of said base can be turned sufficiently so as to move the ribs or bars 10 thereof out of alignment with the ribs or bars of the other sections, so as to pinch portions of the resistor 11 between the ends of said bars or ribs. After this tying of the heating element or resistor 11 has been effected, the nut 9 can be tightened up and so hold the various sections of the base 2 in desired relative relationship. The ends of each rib or bar 10 are undercut as shown at 12, and the extremity 13 of each rib or bar projecting beyond the undercut portion thereof will come in contact with the resistor and act as a clamp to, in effect, tie the same to the base 2 as before mentioned.

Integrally formed with the flanged member 7 is a post 14, which preferably, though not essentially, projects above said flanged member 7. This post is provided with two passageways 15, one only of which is shown

in Fig. 1, and through these passageways is passed the ends of the resistor 11 (see Fig. 1), which ends are secured to the binding posts 16 (only one of which is shown), which are carried by the post 14.

17 (see Fig. 1) is a plate which forms the top of the liquid chamber 18 at the bottom of the heater. This plate is centrally apertured as shown at 19, and threaded in this aperture is a tubular member 20, the upper end of which is closed by a cap 21 integrally formed therewith or as shown. The heating unit is positioned for use as shown in Fig. 1, by passing it over the tubular member 20, which tubular member is received by the tubular member 5. The said heating unit rests upon the plate 17 through the medium of its ring 6.

Located within the tubular member 20 is 20 a conduit 22 which is formed of a pipe bent back upon itself, and having its discharge end 23 preferably located at the bottom of the tubular member 20 and discharging into the liquid chamber 18. This conduit is carried by pipe couplings 24, portion of which 25 projects through the liquid chamber 18, and also through the outer casing 25 of the liquid heater. As shown in Fig. 1, the pipe couplings 24 are detachably coupled to pipe couplings 26 which are carried by any suitable 30 liquid tank 27.

The base 2, which comprises the heating unit, is surrounded by a liquid chamber composed of inner and outer walls 28 and 29, 35 spaced apart to permit liquid to flow therebetween. The lower ends of the walls 28 and 29 are attached to the plate 17 as shown at 30 and 31, (as by brazing to make liquid tight joints) in such position that the passageways 32 formed in the plate 17 will conduct liquid into said liquid chamber between the walls thereof. The upper ends of the walls 28 and 29 are suitably secured together to make a liquid tight joint, though of course 40 it must be understood that said walls 28 and 29 may be integrally formed, thus avoiding the necessity of joining them together at their upper ends.

Liquid enters the heater through pipe couplings before mentioned and then passes up 50 and down through conduit 22 and into the liquid chamber 18, whence it passes through the passageways 32 into the liquid chamber formed by the walls 28 and 29, and then out 55 of the heater through the pipe couplings 33, opening through the wall 29 to the liquid tank 27.

From what I have just described it is clearly seen that I utilize simultaneously heat 60 interiorly and exteriorly of the heating unit already described.

The outer casing 25 is spaced apart from the outer wall 29 of the liquid chamber surrounding the heating unit, and the space 65 between these parts is filled with any suitable

heat retaining material, such as asbestos or mineral wool, or powdered soap stone.

The outer casing 25 extends above the top of the liquid chamber surrounding the heating unit so that a cap or cover 34 may be removably attached thereto. This cap or cover 70 may be made in any suitable way so as to retain as much heat as possible within the heater.

The portion of the casing 25 projecting above or beyond the heating unit is slotted as shown at 35 so as to permit the binding posts 16 to project laterally of the heater.

By removing the cap or cover 34 access is had to the heating unit, and the same may be withdrawn from the heater for any purpose.

Since the tubular member 20 has threaded connection with the plate 17, this tubular member may be removed, and thus permit access to the liquid passages in the heater for 80 cleansing purposes.

As shown clearly in Fig. 3, the conduit 22 does not fill the tubular member 20, and therefore liquid will enter this tubular member and surround the conduit 22. When the liquid flowing as indicated, enters the conduit 22 it is at its lowest temperature, and by the time it passes into the liquid chamber 18 its temperature will have been considerably raised so that by the time it flows out of the heater through the pipe couplings 33, its temperature 85 will be very high.

Since the liquid entering the tubular member 20 and surrounding the conduit 22 must pass out of said tubular member 20 through the opening through which it entered thereinto, the conduit 22 will be surrounded constantly by a highly heated body of liquid, 90 which may sometimes be change into steam.

In Fig. 4, the heating unit embraces a central core 70. The resistor or heating element 11 is wound around said central core, and then a tubular member 71 is slipped over the core 70 to retain the convolutions of the resistor in place. This tubular member 71 is slotted as shown at 72 to permit the resistor or heating element to be wound around the outside of said tubular member. A tubular member 73 is placed around the tubular member 71. To hold the said central core and 100 tubular members together I utilize a cap 40" and a bottom plate 74. The cap 40" and the plate 74 are provided respectively with flanges 75 and 76, which fit around the upper and lower ends of the tubular member 73. The parts just described of the heating unit 105 are made of suitable insulating material, such as porcelain, and in order to tie the various parts described together, I locate in the central passageway of the central core 70, the tubular member 5 which also passes through the cap 40" and the plate 74. Preferably 110 removably carried by the lower and upper ends of said tubular member are rings or nuts 6 and 9.

Formed in the cap 40" are openings such as 15 of Fig. 1, to permit the ends of the resistor or heating element to be passed through said cap and attached to the binding posts 5 16 which are supported by a post 14. The construction just described provides a heating unit which can be readily removable since it is not attached in any manner to the other parts of the heater.

10 Within the tubular member 5 is the tubular member 20 of Fig. 1, and this tubular member contains the conduit 22. The walls 28' and 29' of the liquid chamber in this species are connected at their lower ends by liquid 15 tight joints with the plate 17, which is apertured to permit the flow of liquid into said liquid chamber.

Though I have indicated that the liquid enters the heater through the pipes and couplings 24, it will be understood that the direction of flow of the liquid can be reversed without departing from the spirit of my invention. In that case, the liquid in the conduit 22 flowing into the pipe couplings 24 will have a 25 higher temperature than that of the liquid in the other parts of the heater.

The prior art shows efforts to utilize the heated chambered core or interior of a base or support for a resistor, but since the liquid 30 is desired to heat flows at large therethrough at a speed substantially that of any other part of the liquid stream in the heater, this chamber is kept constantly flushed and therefore no relatively-confined volume-constant 35 body of highly-heated fluid is available therein to be used as I use it, and for this very reason the forms of my heater herein disclosed possess the maximum of efficiency and are very economical in current consumption.

40 In all of these species, there is no outlet for liquid at the upper or outer end of the tubular bases or supports therein shown, and since the conduits 22 are shaped and preferably terminate, as shown, the passage of 45 liquid therethrough does not flush the said bases or supports out, as would be the case were these conduits to terminate a short distance from the upper or outer closed ends of said bases or supports. Therefore the heat 50 stored in the liquid or vapor within said tubular bases or supports will very largely accelerate the heating of the liquid passing through said conduits. This is an important feature of my invention.

55 In this specification and the claims forming part thereof the term "volume-constant" is used to mean that while there may be a change in the state of the fluid (this will of course depend upon the temperature thereof) 60 within the chambered core or base, the said chamber will, in use, always be filled with a fluid because of the common inlet-outlet opening which is preferably directly in communication with the current of liquid passing 65 through the heater.

The term "relatively-confined" is used herein to convey the idea of a body of fluid which while housed within a chamber having a common inlet-outlet opening has communication with the current of liquid flowing 70 through the heater by means of said common opening, but yet is incapable of freely entering into the circulation thereof.

The term "confined stream", as used herein means a stream of liquid passing through 75 a conduit located in or passing through a chamber.

While I have specifically illustrated and described means to preferably utilize electrical energy as a source of heat, (because it is 80 safer and more widely available than gas) it must be understood that I may use gas or other fuel as a source of heat, and that the utilization of any suitable means to generate heat from gas or other fuel falls within the 85 term of my disclosure and of my claims.

While I have described what I consider to be the best embodiments within my invention, it must be understood that the principle thereof may be embodied in still other forms, 90 and I require not to be limited beyond the requirements of the prior art and the terms of my claims.

What I claim as my invention is:

1. The method of heating liquid from a 95 source of heating medium which consists in passing a homogeneous body of liquid through intercommunicating passageways while maintaining a substantially inert volume-constant body of this body of liquid in one portion thereof, which body is heated to, and maintained at, a high temperature by said heating medium, and extracting the heat from said body of fluid without displacing the same, to heat a confined cooler body of 100 this homogeneous body in one portion of said intercommunicating passageways passing through this heated body of fluid.

2. The method of heating liquid from a 105 suitable source of heating medium which consists in impounding a body of liquid within a blind chamber opening from a chamber through which a homogeneous liquid is flowing, and therein transforming it into, and maintaining it as, a substantially volume-constant body of highly-heated fluid, and passing a relatively-confined cooler body of 110 the flowing liquid through said body of highly-heated fluid to be heated thereby, and without displacing the same.

3. The method of heating liquid from a 115 suitable source of heating medium, which consists in providing a flow of a homogeneous liquid into and through certain intercommunicating passageways and at the same time diverting portion of the primary flow to fill a blind section of said passageways where it is transformed into, and maintained as, a substantially volume-constant quiescent body of 120 highly-heated fluid, and passing a relatively- 125

130

confined cooler body of the flowing liquid through said body of highly-heated fluid to be heated thereby, and without displacing same.

- 5 4. The method of heating liquid from a suitable source of heating medium, which consists in providing a flow of a homogeneous liquid into and through certain intercommunicating passageways and at the same time
10 diverting portion of the primary flow to fill a blind section of said passageways where it is transformed into, and maintained as, a substantially volume-constant quiescent body of highly-heated fluid, and passing a relatively-confined cooler body of the flowing liquid from the open end of said blind passageway to the closed end thereof, and then from this latter end back to said open end where it passes into the stream of flowing liquid outside said blind passageway.
